UNITED STATES PATENT OFFICE.

FRED H. KLOEPER, OF LANCASTER, KANSAS.

ATTACHMENT FOR OIL-FOUNTS.

1,227,629.

Specification of Letters Patent. Patented May 29, 1917.

Application filed December 18, 1916. Serial No. 137,657.

To all whom it may concern:

Be it known that I, FRED H. KLOEPER, a citizen of the United States, residing at Lancaster, in the county of Atchison, State 5 of Kansas, have invented certain new and useful Improvements in Attachments for Oil-Founts; and I do hereby declare the following to be a full, clear, and exact description of the invention, such as will enable others skilled in the art to which it 10 appertains to make and use the same.

This invention relates to an attachment for the oil fount or reservoir of oil cook stoves and the like and is directed more 15 particularly to a device adapted for association with the screw cap or closure for the filling opening of the fount, by which said closure may be conveniently removed and replaced and by which the fount may 20 furthermore be readily carried, there being thus obviated the necessity for soiling the hands when removing, filling and replacing the fount upon the stove.

In oil founts of this character, there is 25 embodied in the screw closure thereof, a spring pressed valve, the stem of which projects outwardly from the closure a sufficient distance to be operated by the stove when the fount is positioned thereon, 30 the valve being thus held in open position against the action of the spring.

As this construction of valve with but slight variation is common to oil founts of 35 the character specified it is my purpose to utilize the spring and valve stem thereof to assist in maintaining the attachment in operative relation to the screw closure, it being thus possible to produce an article capable of general application while its 40 construction will at the same time be rendered extremely simple and economical.

A further purpose of the present invention is to provide a combined handle and screw closure remover for oil founts which 45 may be associated therewith without alteration of any character and which may be readily attached and detached as desired.

With the above and other objects of similar nature in view, the invention consists in the construction, combination and arrangement of parts set forth in and falling within the scope of the appended 50 claims.

In the drawing:

55 Figure 1 is a front elevation of the attachment applied to an oil fount.

Fig. 2 is an edge view thereof showing the handle in position to be detached from the screw closure,

Fig. 3 is a vertical section taken on the 60 line 3—3 of Fig. 2, and

Fig. 4 is a perspective view of the attachment removed from the fount.

Referring now more particularly to the accompanying drawing, the attachment is 65 designated generally at 5 and consists of a handle including convergent leg portions 6 and a connecting bight portion 7, the free ends of the leg portions being extended in spaced parallel relation and being similarly provided with bayonet slots 8 opening through corresponding edges thereof.

Connecting as at 9 to the leg portions 6 in spaced substantially parallel relation to the bight 7 is a transverse brace bar 10, 75 and arranged centrally of the bar and secured thereto by a rivet 11 or other suitable means is a cup shaped member 12, said member opening toward the free ends of the legs 6 and being adapted to a purpose which will hereinafter be explained. The attachment further consists of a split metal clamping ring 14, terminating at its 80 ends in spaced apertured ears 15 through which is passed a clamping bolt 16, there being also struck outwardly from this ring at diametrically opposite points, trunnions 17 detachably engageable in the respective bayonet slots 8 above described.

Attention is now directed to Figs. 1, 2, 90 and 3 of the drawing as illustrating the application of the attachment. In these figures there is shown an oil fount 18 of conventional type, provided with the usual filling neck 19 with which is engaged a 95 screw closure 20, said closure being provided with an outlet opening 21 normally closed by a valve 22, the stem 23 of the valve projecting outwardly through said outlet opening and having engaged thereabout a coil spring 24 which serves to urge the valve to closed position.

In applying the attachment to the fount, the ring 14 is disposed to encircle the closure 20 and is detachably clamped thereto 100 by means of the bolt 16. This ring is designed to be permanently attached to the closure 20 and is in such position as to interfere in no way with the prescribed use of the fount.

110 It is to be understood that the normal position of use of the fount is the reverse of

that illustrated in Fig. 1, the neck thereof projecting into the supplemental reservoir (not shown) of the stove while the valve 22 is held in open position by engagement 5 of the stem 23 with the bottom of the reservoir. At such times the handle portion of the attachment is detached from the ring 14 and hung in some convenient locality either upon or adjacent the stove.

10 Thus when the oil in the fount shall have become exhausted, the same is lifted from the stove and inverted as shown in Fig. 1, the handle portion of the attachment being then operatively engaged with the closure 20 15 by positioning the cup 12 to receive the end of the stem 23, and pressing the same downwardly against the spring 24 until the trunnions 17 enter the bayonet slots 8 after which the pressure is removed to permit the 20 parts to assume the position illustrated in Fig. 1. It will be evident that the handle is now securely held in an upright position on the closure 20 and that by rotating the same the latter will be unscrewed from the 25 neck 19. After filling the fount, the closure is replaced and the fount lifted and carried through the medium of the handle back to the stove, after which the handle is disengaged from the closure as will be evident. 30 By this arrangement employment of the fingers to remove and replace the closure is obviated, and soiling of the hands accordingly prevented.

Copies of this patent may be obtained for five cents each, by addressing the "Commissioner of Patents, Washington, D. C."

What I claim is:

1. A combined carrier and wrench for receptacles having threaded closures provided with a spring pressed valve including a stem projecting outwardly from the closure; consisting of a member forming a carrying handle and provided with means for detachable engagement with the threaded closure of a receptacle, said member further having means to engage the stem of the valve in such manner that the spring thereof will maintain the member detachably applied to the closure. 35

2. The combination with a threaded can closure having a valve provided with a spring forcing the valve outwardly to its seat, said valve being further provided with an outwardly projecting stem; of a combined carrier and wrench for said closure comprising a bail forming a carrying handle and having legs provided with means for detachable engagement with the closure, said carrier further having means to engage the stem and compress the spring during the 50 application and removal of the carrier to and from the closure.

In testimony whereof, I affix my signature, in the presence of two witnesses.

FRED H. KLOEPFER.
